UNITED STATES PATENT OFFICE.

LOUIS BAECKER, OF DETROIT, MICHIGAN.

PRINTER'S GALLEY.

SPECIFICATION forming part of Letters Patent No. 374,109, dated November 29, 1887.

Application filed November 9, 1886. Serial No. 218,401. (No model.)

To all whom it may concern:

Be it known that I, LOUIS BAECKER, of Detroit, county of Wayne, State of Michigan, have invented a new and useful Improvement 5 in Printers' Galleys; and I declare the following to be a full, clear, and exact description of the same, such as will enable others skilled in the art to which it pertains to make and use it, reference being had to the accompanying 10 drawings, which form a part of this specification.

My invention relates to improvements in printers' galleys; and it consists in the novel features of construction and combination of 15 parts hereinafter fully described, and definitely pointed out in the claims.

In the drawings forming a part of this specification, Figure 1 is a plan view illustrating my invention, and Fig. 2 is a cross-section. 20 Fig. 3 is a separate view.

I carry out my invention as follows:

A represents a galley of any desired construction. A' and A² are its upwardly-extended sides, and A³ A⁴ its upwardly-extended ends, 25 said sides and ends forming a flange about the base A⁵.

The construction of the end piece, A³, will be more fully explained in a following paragraph.

B represents a movable bar extending longitudinally across the galley for the purpose of locking the type in place when so desired. This bar is provided with a series of ears, b, preferably six in number, although I do not wish to be limited to any specified number.

35 C illustrates a series of cams, preferably elliptical in form and three in number, although any proper form and number of said cams may be employed. These cams are eccentrically engaged with said ears b, respectively, and are also united together by an operating-rod, D, so as to be simultaneously operated by a lever, D'.

The side of the galley is provided with a rack-bar or similar device for holding the lever in any given position, as shown at a. These cams have a bearing against the adjacent side of the galley, as shown.

45 The bar B may have any suitable guides to control its lateral movement. It may either 50 move in guides in the end pieces, A³ A⁴, (indicated in dotted lines at a' a''), or the side A²

may be provided with studs a³, upon which the bar is sleeved; or the base of the galley may be slotted, as shown at a⁴, to receive a guide pin or head, b', upon the said bar, as indicated in 55 Fig. 2.

The operation of the device will now be seen. If it is desired to lock the type in the galley, the lever D is thrown in the proper direction, and the bar B is thereby crowded upon the type by means of the eccentrically-connected cams C; and as these cams are preferably located toward the ends and intermediate of the ends of 65 said bar the bar will be forced evenly along its entire length against the type, this position being indicated in dotted lines. Vice versa, when it is desired to unlock the type, the lever is thrown in the opposite direction and the bar B assumes the position shown in full lines. Thus the work is done quickly and 70 readily and in a thoroughly efficient manner, dispensing with the unsatisfactory process of wedging the bar upon the type, commonly in 75 vogue.

The bar A³ is hinged at one end, as shown at a⁵, the hinge being preferably provided with a spring, a⁶, arranged to close the said bar automatically when it is free to move. To hold the said bar A³ open, the rod D is provided with any suitable catch, E, constructed 80 to engage the said bar in any proper manner, and to release its hold upon the said bar when the rod is moved to close the locking-bar upon the type. The catch E holds the bar A³ open until the bar B is to be adjusted upon the type. 85

To maintain the engagement between the catch E and bar A³, the former may be made hooked at its end to catch over a slight projection or lug, e, on the bar, as shown in Fig. 1. To withdraw the said bar from the 90 type I prefer to employ springs F F', arranged to throw open the said bar when the lever is released from the rack-bar.

What I claim is—

1. The combination, with a printer's galley, 95 of a movable bar, B, guides to control the movement of said bar, and a series of cams connected by an operating-rod, substantially as described.

2. The combination, with a printer's galley, 100 of a movable bar, B, a series of elliptically-shaped cams eccentrically connected with said

bar, and an operating-rod uniting said cams, said cams having a bearing against the adjacent side of the galley, substantially as described.

3. The combination, with a movable locking-bar, of a series of cams connected by an operating-rod, and springs to automatically open said bar, substantially as described.

4. The combination, with a printer's galley, of a hinged end bar, A³, substantially as described.

5. The combination, with a printer's galley, of a hinged end bar, A³, a spring to close said bar, and a fastening device for holding said end bar open, substantially as described.

6. The combination, with a printer's galley, of a hinged end bar, A³, a movable locking-bar, B, a series of cams connected by an operating-rod for closing said locking-bar, said rod provided with a spring-catch to engage said bar A³ and automatically release the same upon moving said rod to close the bar B, substantially as described.

In testimony whereof I sign this specification in the presence of two witnesses.

LOUIS BAECKER.
